UNITED STATES PATENT OFFICE.

RUDOLPH B. COLONNA, OF HAZLETON, PENNSYLVANIA.

DISPLAY-STAND.

1,387,765.

Specification of Letters Patent. Patented Aug. 16, 1921.

Application filed August 28, 1920. Serial No. 406,591.

To all whom it may concern:

Be it known that I, RUDOLPH B. COLONNA, a subject of the King of Italy, residing at Hazleton, in the county of Luzerne and State of Pennsylvania, have invented certain new and useful Improvements in Display-Stands, of which the following is a specification.

This invention relates to store furniture and has special reference to stands for displaying merchandise in an attractive manner. A particular object of the invention is to provide a display stand of inexpensive construction which may be readily moved from place to place and which will permit merchandise of various kinds to be displayed interchangeably.

The invention is illustrated in the accompanying drawings and will be hereinafter fully set forth.

20 In the drawings—

Figure 1 is a perspective view of a display stand embodying my improvements;

Fig. 2 is an enlarged detail perspective view of the upper end of the post or standard;

Figs. 3, 4, 5, 6 and 7 are detail views showing different forms of the merchandise-supporting arms.

In carrying out my invention, I employ 30 a base 1 which is provided with spaced feet 2 whereby it may be readily supported upon the floor of a store room or of a show window and may be weighted so that it will be held against accidental tipping but will have a 35 small area of contact with the floor so that marring of the finish upon the floor will be minimized. Rising from the base 1 is a post or standard 3 which will preferably be given an ornamental outline, as shown in 40 the drawings, and which may be hollow to permit wires to be run therethrough to carry current to an electric light (not shown) at its upper end. To the upper end of the post or standard 3, I secure a head 4 which, in 45 the present instance, is shown as a circular block or disk. This head is removable so that heads of various shapes and sizes may be employed interchangeably and the display thereby varied according to the wishes 50 of the merchant. In the illustrated embodiment of the invention, threaded rods or bolts 5 are fitted in the upper end of the post or standard 3 and project above the same and the head 4 is provided with spaced openings 55 to engage over the said rods whereby the head may rest upon the upper end of the

post and will be held against turning thereon by the rods. Wing nuts 6 are fitted on the upper threaded extremities of the rods 5 and are turned home against the head 4 to 60 secure the head upon the post. Through the head, adjacent the edge thereof, are formed vertical openings 7 and 8 which extend around the entire perimeter of the head and are of different diameters so that supporting arms of various diameters may be engaged in the head. In the circular edge of the head, I provide radial sockets 9 which are internally threaded and lead into the openings 7 and 8. If so desired, internally 70 threaded metallic bushings may be inserted in the sockets 9 to minimize wear or the entire head may be of metal. Near the upper end of the post and aligned vertically with the openings 7 and 8, retainers 10 are 75 secured around the post which retainers may conveniently be screw eyes threaded into the post, as will be readily understood. Near the lower end of the post, I provide vertical 80 series of supporting retainers 11 which may also conveniently be screw eyes driven into the post and circumscribing the same. The merchandise to be displayed is supported by display arms consisting of rods or tubes 12 each having one end turned downwardly, as 85 shown at 13, to enter and pass through one of the openings 7 or 8 in the head 4. The terminal portion 13 is preferably disposed on a straight line so that it will pass through the openings 7 or 8 as the case may be and 90 also engage one of the sockets or retainers 10, the arm being thus firmly supported and held against rocking in a vertical plane. A set screw 14 is fitted in each socket or opening 8 to bind against the adjacent terminal 95 member 13 and thereby firmly secure the same within the head. The outer end of the display arm 12 is bent upwardly, as shown at 15, and upon the upper extremity of this vertical terminal 15 is provided a rest upon 100 which the merchandise may be placed or over which it may be draped. In Fig. 1, I have shown the display rest 16 as in the form of a disk which may, if desired, be permanently attached to the arm. In Fig. 5, I 105 have shown a similar embodiment of the invention, but the rest 17 is rectangular and larger than the disk 16. The disks 16 are adapted for the display of small articles such as cups or small vases, while the plate 17 110 will carry larger articles, being specially adapted to have shelves for the display of

dry goods secured thereto. In Fig. 3, I have shown a further adaptation of the invention in which the outer terminal member of the display arm is hollow, as shown at 18, 5 and receives the stem 19 of a head or block 20 which is equipped with openings 21 through which screws or similar fastenings may be inserted to secure any desired form of merchandise holder to the head. The 10 stem 19 is vertically adjustable in the terminal 18 and is held in a set position by a set screw 22 mounted in the end of the terminal and bearing against the stem. It is frequently desirable to have the display arms 15 upon a particular post all of one size but have the merchandise in different horizontal planes, and this result can be easily attained by using the form of the invention illustrated in Fig. 3 and just described. In 20 Fig. 4, I have shown a display arm in which the outer terminal is threaded, as shown at 23, to receive an attaching head 24 which is in the form of a spider and to which any desired form of merchandise holder may be secured. The spider also may be utilized as 25 a merchandise holder inasmuch as the arms thereof are dished so that the spider is in the form of a bowl in which articles may be set.

30 It will be readily understood that the display arms may be given any desired form between their ends and may be of any desired length and in the drawings I have illustrated arms of different shapes and 35 lengths fitted upon a single post so that the articles placed upon the stand for display will appear to have a hap-hazard relation to each other and this hap-hazard effect is very attractive with some classes of goods. 40 In all the forms of the invention shown in the accompanying drawings, the intermediate portion 25 of the display arm extends in a general downward and outward direction thereby presenting a bight or bend 26 over 45 which ribbons or similar materials may be draped. The adaptability of the device to permit draping may be utilized to display textile goods and also to ornament the display stand so as to set off, by contrast, the 50 articles placed upon the several merchandise rests.

In Fig. 6, I have shown a rest or merchandise carrier which is especially adapted for draping of textile goods and consists of 55 divergent arms or bars 27 disposed radially to the terminal of the display arm and intersecting at said terminal. The ends of these several arms 27 may be given an ornamental configuration, as indicated at 28.

60 When the display arms are long, it is advisable to employ braces 29 engaged at their outer ends in openings in the arms and having their inner ends engaged in a cup 30 on

the post so that sagging or springing of the arm will be prevented. 65

In Fig. 7 I have shown the display arm as provided with a horizontal outer terminal 31 on which is a clamp 32 to engage and secure a ball 33 on the lower end of a stud 34 depending from a disk 35. A merchandise 70 holder of any desired form may be secured upon the disk 35 and the ball and socket joint permits the same to be adjusted to any desired angle.

From the foregoing description, taken in 75 connection with the accompanying drawings, it will be seen that I have provided an exceedingly simple display stand which will be light so that it may be easily carried from place to place and will be stable when 80 set up. The several display arms may be very easily and quickly fitted to and removed from the stand so that an arm of one shape may be substituted for an arm of another shape at will without any waste of time and 85 the device thereby easily adapted for the display of any desired goods.

Having thus described the invention, what is claimed as new is:

1. A display stand comprising a post, vertically alined retainers on the post, a cup on the post below the retainers, display arms having depending terminals at their upper ends to be inserted through the retainers, and bracing arms having their lower ends 95 engaged in said cup and their upper ends engaged with intermediate portions of the display arms.

2. A display stand comprising a post, a head upon the post provided with display-arm retainers and having sockets in its edge intersecting said display-arm retainers, other display-arm retainers disposed below and alined vertically with the first-mentioned display-arm retainers, display arms 100 having upper depending terminals to be inserted through the vertically alined retainers, merchandise holders carried by the outer ends of the display arms, and set screws mounted in the said sockets and bearing 110 upon the upper terminals of the display arms.

3. A display stand comprising a post, a head removably secured upon the upper end 115 of the post and having vertical openings therethrough adjacent its edge, display arms each having a vertical terminal adapted to be inserted through one of said openings, retainers on the post below the head to be engaged by said terminals, means for securing 120 the terminals against movement in the said openings, and merchandise holders carried by said arms.

In testimony whereof I affix my signature.

RUDOLPH B. COLONNA. [L. S.]
